(57) **CLAIM**

The ornamental design for a staircase slide, as shown and described.

DESCRIPTION

FIG. 1 is a rear perspective view of a staircase slide, showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is an enlarged detail view of area 8 in FIG. 1.

The broken lines in the drawings illustrate the portions of the staircase slide, which form no part of the claimed design. The dash-dash lines in the drawings illustrate the portions of the staircase slide, which form no part of the claimed design. The dash-dot-dash broken lines encircling the enlarged view depict the bounds of the enlarged view and form no part of the claimed design.
